UNITED STATES PATENT OFFICE.

CLARENCE W. WHITE, OF NORTH BENNINGTON, VERMONT.

DESIGN FOR A STEERING POST AND WHEEL FOR CHILDREN'S VEHICLES.

52,815.

Specification for Design.

Patented Dec. 24, 1918.

Application filed March 8, 1916. Serial No. 82,935. Term of patent 14 years.

To all whom it may concern:

Be it known that I, CLARENCE W. WHITE, a citizen of the United States of America, residing in North Bennington, county of Bennington, and State of Vermont, have invented a new, original, and ornamental Design for a Steering Post and Wheel for Children's Vehicles, of which the following is a specification, reference being had to the accompanying drawing, forming part thereof.

Figure 1 is a side view of a steering post and wheel illustrating my new design, and

Fig. 2 is a front view thereof.

I claim:

The ornamental design for a steering post and wheel for children's vehicles as shown.

In witness whereof I have signed this specification in the presence of two subscribing witnesses.

CLARENCE W. WHITE.

Witnesses:

IRVING COBB,
HARRIE C. WHITE.
